DESIGN FOR A DISPENSING COOLER FOR BOTTLED BEVERAGES OR THE LIKE

Chester A. Frick, Muncie, Ind., assignor to Glasscock Brothers Mfg. Co., Muncie, Ind., a corporation of Indiana

Application May 29, 1933. Serial No. 48,239

Term of patent 7 years

To all whom it may concern:

Be it known that I, CHESTER A. FRICK, a citizen of the United States, residing at Muncie, in the county of Delaware and State of Indiana, have invented a new, original, and ornamental Design for a Dispensing Cooler for Bottled Beverages or the like, of which the following is a specification, reference being had to the accompanying drawing forming a part thereof.

The figure is a perspective view of a dispensing cooler for bottled beverages or the like, showing my new design.

I claim:

The ornamental design for a dispensing cooler for bottled beverages or the like, as shown.

In witness whereof I, CHESTER A. FRICK, have hereunto set my hand at Muncie, Indiana, this 24th day of May, A. D. one thousand nine hundred and thirty-three.

CHESTER A. FRICK.
